ELECTRIC HEATING SYSTEM FOR FLUIDS

Filed Nov. 28, 1930

UNITED STATES PATENT OFFICE

HERBERT HEROY, OF BELMAR, NEW JERSEY

ELECTRIC HEATING SYSTEM FOR FLUIDS

Application filed November 28, 1930. Serial No. 498,875.

This invention relates to an electric heating system for fluids and is intended primarily for heating liquids but it may be used for heating fluids of a gaseous nature as well as liquids. Its objects are to concentrate the heat from an electric heating coil on a comparatively thin section of fluid which is continually in motion; another object of the invention is to provide a container with a plurality of chambers, one of which contains a heating coil and in which the fluid is passed alternatively in opposite directions through said chambers; other objects of the invention reside in the construction and arrangement 15 of the elements of the device as more particularly described in the following specification and illustrated in the accompanying drawings, in which;

Fig. 1 is a sectional elevation showing the 20 system complete, and;

Fig. 2 is a horizontal cross-section, on line 2—2, Fig. 1.

This invention is disclosed in U. S. Patent 1,809,899 of June 16, 1931. In this patent 25 the electric heating unit is used to heat, or boil water on the flash-boiler principle for infusion machines. In this construction the source of supply is connected to a central tube which is closed at both ends but is provided 30 with perforations at the end opposite the supply so that a fluid entering this tube, under pressure, passes through it and through the perforations to the chamber enclosing the heating coil. This chamber is enclosed 35 by an outer tube also closed at both ends, but having perforations at the end opposite to the position of the perforations in the central tube and this outer tube is enclosed by a spaced housing, having a delivery orifice at 40 the end opposite the perforations in the outer tube. The result is that the fluid, under pressure, is continually moving in the inner tube, which is heated by the surrounding heating coil, then it is spread out through the perforations and passes in the reverse direction 45 over the heating coil and again is spread out, by the perforations, in the outer coil and passes in the reverse direction around the outer tube to the delivery orifice. In this 50 way the fluid is spread out and exposed to a

large heating area so that high temperatures may be obtained in very short intervals of time. The electric coils of the type used in devices of this kind are liable to become injured if the current is turned on without some means of carrying away the heat and, for this purpose, the valve which controls the supply, also controls the electric current so that when the valve is closed the electric circuit is open and when the valve is open the electric circuit is closed. It should be observed that the passage of the fluid, through the device, may be reversed without materially effecting the results, that is, the supply may be connected to the delivery orifice and the delivery obtained from the supply orifice. 55 60 65

In the construction of the device the cylindrical housing is provided with a pair of removable end caps, or a base and top, which hold the device together and provides a space 70 at the top between the chambers for the free circulation of the fluid.

In the drawings, 11 is the housing, which is preferably cylindrical in form, with flanged ends to which the cap 12 is secured at 75 the upper end and the cap or base 13 is secured at lower end. A central tube 15 is screwed into the base 13 at 14 and connects directly with the supply pipe 17. The top of this tube is provided with perforations at 16, leading into the chamber 19 which is enclosed by the outer tube 24 seated on a ledge on the base 13 and held in position by the projection 28 of cap 12 engaging the closed upper end of the tube. This tube, when in position, is closed at both ends and is provided with perforations at 27 which connects the chamber 19 with the chamber 25. The perforations 27, it will be noted, are in the opposite position relative to the perforation 16 so that fluid entering by the delivery pipe 17 passes through the central tube 15 in the direction of the arrows through the apertures 16 and in the reverse direction through chamber 19 to the apertures 27 and through chamber 25, in the reverse direction to the movement in chamber 19, to the delivery orifice 26. 80 85 90 95

A heating coil 20, 21 is provided in chamber 19 and is preferably constructed in a 100

double spiral, as shown. The stock of the heating coil is a commercial product, adapted to this invention. The ends of this coil are led out through suitable gaskets, secured by the caps 22 and 23, on each end and the two coils are connected in multiple circuit by the wires 31 and 32 connecting to transformer 33, the primary of which is controlled by the switch 34 connected to the supply mains 35. Switch 34 is, preferably, connected by rod 36 with an extension 37 of the valve 18 in the supply pipe 17. When the valve is closed, switch 34 is open and when the valve is moved to the open position the switch 35 is closed.

15 It will be noted that the system may be subject to considerable pressure, either from a water or air supply, and to resist this pressure, tube 15 is securely fastened to the base 13 while the tube 24 is held in position by the housing.

20 25 This invention admits of a variety of applications and is intended to cover a full range of equivalents.

Having thus described my invention, I claim:

30 35 40 45 50 55 60 65 1. An electrical heating system for fluids comprising a cylindrical housing, a pair of end caps for said cylinder, a central tube in said housing having one end screwed into one of said caps opposite a fluid supply pipe and the opposite end closed but provided with perforations at the closed end, an electric heating coil surrounding said central tube, an outer tube of smaller diameter than said cylindrical housing and longer than said center tube enclosing said heating coil and having one end closed and the opposite end provided with perforations at the end in the opposite position to the perforated end of said central tube and resting in a groove in one of said end caps and a fluid delivery pipe connected to an aperture in said cylindrical housing.

2. An electric heating system for fluids comprising a cylindrical housing having a base and a top, a central tube in said housing secured to said base and closed at the ends, a fluid supply pipe connected with the interior of said central tube, an electric heating coil surrounding said central tube, an outer tube of smaller diameter than said housing enclosing said heating coil and central tube and closed at one end and having the opposite end resting in a groove in said base and a projection on said top engaging the closed end to hold said tube in place and a fluid delivery pipe connected to an aperture in said housing, said central tube being perforated at the end opposite the supply connection and said outer tube being perforated at the end in the opposite position to the perforated end of said central tube.

In testimony whereof I affix my signature.
65 HERBERT HEROY.
